UNDERWEAR

Asa J. Harwood, Richmond, Ind., assignor to The
Atlas Underwear Company, Piqua, Ohio, a cor-
poration of Ohio

Application May 20, 1935, Serial No. 22,355

4 Claims. (Cl. 2—78)

This invention relates to undergarments and is concerned more particularly with a novel union suit which affords the advantages of athletic underwear consisting of a shirt and shorts without the disadvantages inherent in such a combination.

The new garment is constructed to fit the body snugly while permitting complete freedom of body movement. It is therefore made of a yielding fabric, such as knitted material, and it is cut so as to cover the torso only and without leg coverings. With this construction, the garment resembles in appearance the present popular combination of a gymnasium shirt and trunks, but is more comfortable, since the extra thicknesses of material about the body, where the shirt and trunks overlap, are avoided, and the shirt part of the garment being integral with the portion covering the part of the body below the waist, cannot become disarranged.

The new garment comprises front and back portions united along their side edges, and these sections, if desired, may be of a single piece of fabric, being cut, for example, from a length of tubular knitted goods. At the top, the front and back portions are connected by spaced shoulder straps, and the upper edges of the front and back portions between the shoulder straps are formed to provide a neck opening. At the sides of the shoulder straps, these edges of the two portions are cut to form arm openings, so that the upper part of the garment has the general form of an athletic shirt. At the bottom, the edges of the front and back portions are connected by a gusset insert, and to assure the comfort of the wearer, this insert is formed of a material which is stretchable longitudinally. The bottom edges of the front and back portions at either side of the insert extend generally diagonally upward therefrom to the side edges of the garment and are cut with the proper curvature, so that these edges and the edges of the insert define leg openings. At the lower end of the front portion just above the insert, the garment is provided with a fly section of novel construction, and the back portion is made of overlapping upper and lower sections providing a drop seat.

For a better understanding of the invention, reference may be had to the accompanying drawing in which

Fig. 1 is a view of the new garment in front elevation, with parts broken away;

Fig. 2 is a view of the garment in rear elevation with a portion of the drop seat broken away; and

Figs. 3, 4, and 5 are sectional views on the lines 3—3, 4—4 and 5—5 of Fig. 1, respectively.

Referring now to the drawing, the garment as illustrated includes a front portion 10 and a rear portion 11, these portions being united along the side edges 12 of the garment. The front and back portions are preferably made of a yielding fabric and may be advantageously formed of a knitted fabric having wales extending vertically. The front portion is a continuous length of fabric extending from the top to the bottom of the garment, while the back portion is made of an upper section 13 and a lower section 14. The upper and lower sections of the back portion overlap with the upper edge of the lower section lying outside the lower edge of the upper section, so as to form a drop seat. The upper edge of the drop seat is provided with an elastic member 15, which may be a strip of elastic fabric or an elastic cord secured along the edge of the drop seat in any suitable manner. While the front and back portions of the garment may be secured together along the side edges 12 by seams, it is preferable to form the front portion and the top section of the rear portion of a length of tubular fabric, and when such fabric is employed, there is no seam along the sides connecting the front portion and the upper section of the back. The lower section of the back is then secured to the front by seams 16 which extend from the upper edge of the rear section down to the lower end of the garment.

At the top of the garment, the front and back portions are connected by shoulder straps 17, and preferably, the upper edges of both portions are provided with spaced extensions 18 from which the straps extend. Between the extensions 18, the top edge of the front portion is cut low, as at 19, to form the front edge of a neck opening, and on either side of the extensions 18, the top edge of the front portion of the garment extends in generally diagonally downward directions to the side edges of the garment to form parts of armholes. The armholes and the neck opening are finished by means of hems 20, and, if desired, the hems for the armholes and neck openings may continue beyond the extensions 18 and be secured together to form the shoulder straps. One of these straps is in two parts with one part provided with a button-hole and the other with a button 21 so that the strap may be opened to permit the garment to be easily put on and taken off.

The top edge of the back portion of the garment is provided with similar spaced extensions 18 to which the shoulder straps are connected, 55

and between the extensions, the edge dips down as at 22 to form the rear part of the neck opening. At either side of the extensions, the top edge of the rear portion extends in generally 5 diagonal downward directions to the side edges of the garment to complete the armholes.

At the lower end of the garment, the central portions of the bottom edges of the front and back portions are connected together by a gusset 10 insert 23 forming the crotch of the garment. This insert is made of a material which is yielding and, preferably, it is formed of two layers of knitted fabric, the wales of which extend horizontally. At either side of the gusset insert, the 15 edges of the bottom ends of the front and back portion of the garment are cut to form leg openings and they extend in generally diagonal upward directions to the side edges of the garment. To make openings which are comfortable, the 20 edges are formed on a curve with the edges 24 of the rear portion cut on a radius of slightly greater curvature than that on which the edges 25 of the front portions are cut. In order that the garment may fit snugly about the legs at 25 the leg openings, elastic inserts 26 may be secured in place around the openings, these inserts being preferably held in place by the stitching by which the hems 27, finishing the leg openings, are attached.

30 In the garment as illustrated, a fly section 28 of novel construction is provided, this section replacing part of the front portion of the garment at its lower end and being secured in position by a seam connecting it to the forward end of the 35 gusset insert and also by a curved seam extending along the lateral sides of the section and across the top thereof. The section is made of two pieces, 28a and 28b, preferably of knitted goods arranged with the wales vertical, and the 40 adjacent lateral edges of the pieces are free and overlap. The free edge of the outer piece 28b extends in a generally diagonal direction from a point at the top of the fly section at one side of the middle thereof to the bottom of the fly section 45 adjacent one lateral edge of the gusset insert. This diagonal position of the free edge of the outer piece causes the edge thereof to be subjected to a pull at all times when a garment is being worn, and the opening between the two 50 pieces is thereby kept from gaping and the free edge of the outer section does not sag. At the same time, the diagonal free edge of the outer section 28b provides a larger opening than would be available if the free edge were perpendicular 55 to the end of the gusset insert.

In union suits, it is customary to provide a seat opening which may extend generally vertically from the waistline to the lower end of one of the leg sections. In the new garment, there 60 are no leg sections and if a vertical seat opening were employed, it would be too short. Accordingly, the new garment is provided with a drop seat, and since the use of that construction imposes severe strains which might do damage to portions 65 of the garment, particularly when it is made of knitted material, I provide a reinforcement which distributes the strains over wide areas. For this purpose, a strip 29 of fabric is secured to the front section in line with the upper end of the 70 drop seat, the reinforcing strip 29 extending entirely across the front portion of the garment and being secured in position by suitable seams 30. The strip 29 is preferably made of the same material as the remainder of the garment, as 75 for example, of knitted material having vertical

wales. By the use of this reinforcement, the strains imposed on the garment by the use of the seat are transmitted throughout the entire width of the front portion.

It will be seen that the new garment resembles the combination of an athletic shirt and shorts which is now so widely worn, but it is more comfortable than that combination, because it is in one piece and the usual extra thickness of cloth at the waistline caused by the overlapping of the shirt and shorts is dispensed with. The new garment fits snugly without binding since it is made of yielding material, and it affords complete comfort and does not interfere with the movements of the body of the wearer. The new 15 garment accordingly provides the advantages of a shirt-shorts combination and avoids its disadvantages.

I claim:

1. An undergarment of the union suit type 20 which comprises front and back portions, said front portion being continuous from top to bottom of the garment and said back portion consisting of upper and lower sections overlapping adjacent the waistline with the top edge of the lower section 25 being free and providing a drop seat, an elastic reinforcing strip extending across the front of the garment between the side edges of the latter and connected at its ends to the lower section of the back portion at the free upper edge of the latter said front portion and said upper section of the back portion being formed of a single piece of tubular knitted material having vertical wales and said lower section of the back portion being of similar knitted material and secured by stitching 35 to the side edges of said front portion below the waistline and also to the front portion and said upper section of the back portion along the side edges of the garment throughout the overlapped portion of said upper section, shoulder straps connecting the upper edges of said front portion and upper back section, and a gusset insert of a plurality of thicknesses of knitted material with horizontal wales connected to the lower edges of the front portion and lower back section, said lower 40 edges on either side of said insert being cut on diagonally upward curved lines to provide leg openings defined in part by said edges and in part by the side edges of said insert.

2. An undergarment of the union suit type 50 which comprises front and back portions united along their side edges, the front portion being connected to the back portion at the top of the garment by spaced shoulder straps and the back portion comprising upper and lower sections overlapping and providing a drop seat, a gusset insert connecting the central parts of the bottom edges of said portions, said gusset insert being elastic in a direction through the crotch, said garment having leg openings on either side of said gusset 60 insert, and a fly section in the front portion and connected to the forward end of the gusset insert, said fly section comprising two pieces of fabric having their adjacent edges overlapping and free, the free edge of the outer piece extending generally diagonally from a point at the top of the fly section downwardly to the upper front horizontal end of the gusset insert adjacent one of the leg openings.

3. An undergarment of the union suit type 70 which comprises a shirt portion and a trunks portion, said shirt portion and said trunks portion being made of knitted material having the wales running vertically and providing elasticity in a horizontal direction, the upper edge of the trunks 75

portion at the rear being free and providing a drop seat, a reinforcing strip elastic in a horizontal direction connecting the shirt portion to the trunks portion at each side of the front of the garment opposite the upper edge portion of said drop seat, whereby strains resulting from the use of the drop seat will be distributed over wide areas.

4. An undergarment of the union suit type which comprises front and back portions, said front portion being continuous from top to bottom of the garment and said back portion consisting of upper and lower sections overlapping adjacent the waistline with the top edge of the lower section being free and providing a drop seat, an elastic reinforcing strip extending across the front of the garment between the side edges of the latter and connected at its ends to the lower section of the back portion at the free up-

per edge of the latter, said front portion and said upper section of the back portion being formed of tubular knitted material having vertical wales, and said lower section of the back portion being of similar material and secured by stitching to the side edges of said front portion below the waistline and also to the front portion and said upper section of the back portion along the side edges of the garment throughout the overlapped portion of said upper section, shoulder straps connecting the upper edges of said front portion and upper back section, the central portions of the lower edges of said front and back portions being connected by means elastic in a direction through the crotch when the garment is worn, and said bottom portion having leg openings on each side of the crotch.
